WINDOW RUNWAY OR CHANNEL

Carlos J. McKinney, Detroit, Mich., assignor, by
mesne assignments, to The Standard Products
Company, Cleveland, Ohio, a corporation of
Ohio

Application December 5, 1933, Serial No. 700,998

3 Claims. (Cl. 296—44.5)

This invention relates to improvements in window runways or window channel, such as are used in automobile bodies for guiding the slidably mounted, sashless glass windows thereof. More particularly, the present invention relates to the window-cushioning linings of such runways or channel.

The general object of the present invention is the provision of a window runway or channel having an improved window-cushioning lining, said lining being of simple and inexpensive construction, of such character that it retains throughout its unusually long life its original, exceptionally great resiliency or cushioning effects, and which lining does not impede, even when wet, the slideable movements of the window therealong.

A more specific object of the present invention is the provision of a window runway or channel having a window-cushioning lining formed of bristles, such as hogs' bristles, held together in mat-like form by coagulated latex, an adhesive which does not impair the inherent resiliency or springiness of said bristles. If desired, said bristles may be provided with a window-engaging fabric cover.

Further objects of the present invention are in part obvious and in part will appear more in detail hereinafter.

The invention will be readily understood from the following description thereof, reference being had to the accompanying drawing in which

Fig. 1 is a perspective view of a portion of the improved lining of the present window runway or channel, said portion comprising a layer or mat of entwined or entangled hogs' bristles held together in such layer-like or mat-like form by liquid latex; Fig. 2 is a similar view of said layer or mat of bristles provided with a window-engaging fabric cover; Fig. 3 is a perspective view of a portion of the present runway or channel in finished form; and Fig. 4 is a sort of microscopic view of a portion of the entwined or entangled hogs' bristles of the present improved runway or channel lining, showing the manner in which said bristles are bound or tied together by the coagulated latex.

The window runway or channel here illustrated and described is particularly suitable for use in guiding the slidably mounted, sashless glass windows of automobile bodies, said runway or channel comprising a suitable channel-shaped structure, of metal or the like, and a suitable window-engaging lining therefor, said lining being of sufficient resiliency to properly cushion the window against the shocks and jars to which it is usually

subjected without interfering with or impeding the slideable movements of said window.

As here shown, the channel shaped structure of said runway or channel comprises a simple sheet metal member having a base 10 and a pair of generally parallel window-receiving side walls 11 terminating at their outer edges in longitudinally disposed beads 12. Although said member is here shown as of solid form, it may be provided, if desired, with transversely disposed slots, such as are shown in my prior Patent No. 1,876,519, granted September 6, 1932, or in the Gaines Patent No. 1,898,948, granted February 21, 1933, the purpose of said slots being to give said member increased flexibility, as pointed out in said patents and as will be readily understood.

For cushioning the window which said channel shaped structure receives in use thereof, a suitable resilient lining is provided therefor, said lining being longitudinally secured within said structure by the side wall beads 12 thereof, as clearly shown in Fig. 3.

The present improved lining for said channel shaped structure includes a layer or mat 15 of entwined or entangled hogs' bristles bound or tied together, one to another, in such layer-like or mat-like form by coagulated latex, an adhesive which does not impair the inherent resiliency or springiness of said bristles. In Fig. 4, a sort of microscopic view of said entwined or entangled bristles is shown, said bristles, indicated by the reference character 18, being held in such entwined or entangled form by said coagulated latex, indicated by the reference character 19.

In forming this part of the present improved lining, the bristles 18 are arranged in layer or mat form, and the liquid latex is then sprayed thereon, in sufficient quantity to substantially permeate the entire layer or mat of bristles and when dry to effectively bind or tie said bristles together in such layer or mat form.

In the embodiment of the invention here shown, said layer or mat of bristles is provided with a suitable window-engaging cover 21, of felt or other suitable fabric, said cover having its longitudinal edge portions 23 bent or turned around the corresponding edge portions of said layer or mat of bristles, as best shown in Fig. 2.

As shown in Fig. 3, the present improved lining, comprising the layer or mat of bristles and the fabric cover 21 therefor, is longitudinally arranged in the channel shaped structure of the present runway or channel, said lining assuming in cross section a channel shape corresponding to that of said structure. The longitudinal edge

- portions of said lining are clamped within the longitudinally disposed beads 12 of said structure side walls 11, the inner surfaces of said beads lying outside of the planes of the window-engaging surfaces of said lining side walls. If desired and as shown, said lining may be provided with longitudinal stitching 25 at its two fold lines, said lines lying adjacent the junction of the base 10 and the side walls 11 of said channel shaped structure.

Due to the improved lining with which it is provided, the present window runway or channel is capable of receiving and guiding windows of abnormal thickness, the bristles of said lining affording throughout their exceptionally long life a resiliency or springiness which effectively protects all windows from the shocks and jars to which they are subjected in use.

Further features of the present invention will be apparent to those skilled in the art to which it relates.

What I claim is:

1. A window runway or channel, comprising a

generally channel-shaped structure having a base and a pair of window-receiving side walls, and a window-cushioning resilient lining for said structure, said lining being formed of coarse inherently resilient bristles loosely entangled in mat-like form of substantially uniform density.

2. A window runway or channel, comprising a generally channel-shaped structure having a base and a pair of window-receiving side walls, and a window-cushioning resilient lining for said structure, said lining being formed of coarse inherently resilient bristles adhesively held together, by the rubber of a latex solution, in loosely entangled mat-like form of substantially uniform density.

3. A lining for window runways or channels formed of coarse, inherently resilient bristles which are loosely entangled, said bristles being held together in mat-like form by an adhesive in sufficient amount to bind the bristles together but in an insufficient amount to impair the inherent resiliency of said bristles.

CARLOS J. MCKINNEY.
